UNITED STATES PATENT OFFICE.

HOMER HARVEY FULTON, OF CHICO, CALIFORNIA.

FINGER-SHIELD.

No. 888,991.

Specification of Letters Patent.

Patented May 26, 1908.

Application filed October 25, 1907. Serial No. 399,121.

To all whom it may concern:

Be it known that I, HOMER HARVEY FULTON, a citizen of the United States, and a resident of Chico, in the county of Butte and State of California, have invented a new and Improved Finger-Shield, of which the following is a full, clear, and exact description.

This invention has for its purpose the provision of a finger shield for the use of persons who by force of circumstances are compelled to eat with unwashed hands.

The invention further contemplates a shield of such material as paper, which will expand to fit fingers of various sizes and frictionally embrace the same to such an extent as not to drop off, and also in which the finger opening presents a construction to facilitate the insertion of the finger.

Reference is to be had to the accompanying drawings forming a part of this specification, in which similar characters of reference indicate corresponding parts in all the views.

Figure 1 illustrates in perspective the manner in which several of my improved shields are applied preparatory to eating; Fig. 2 is a plan of one of the shields when flattened out; and Fig. 3 is a fragmentary longitudinal section of my improved shield when expanded.

In the construction of my improved shield, I preferably employ a thin sheet material of an elastic nature which is comparatively cheap; such material as crimped or crape paper I find admirably adapted for this purpose. This is made into a stall or jacket 5, of such size as to neatly fit a finger of average size, as best shown in Fig. 2. The inner or open end of this jacket is preferably cut off at an inclination and then folded inwardly upon itself to provide an inwardly-turned flange 6. A jacket thus constructed will, in view of the crimps or corrugations in the paper, expand to fit various size fingers, and frictionally embrace the same to such an extent, as to prevent accidental slipping from the finger when applied. The engagement of

the jacket with the finger will also be augmented by the flange 6, the latter additionally serving to strengthen the jacket around the entrance opening.

By cutting off the ends of the fingers at an inclination, as shown in Fig. 3, and then flattening them out, as in Fig. 2, the jacket may be conveniently opened out and the insertion of the finger therein facilitated, as is obvious.

Instead of constructing the shield from crape paper, the same may be first made of plain paper or other fibrous material, and the crimps or corrugations thereafter formed therein. The character of material may also be considerably modified without departing from the nature of my invention as defined in the claims annexed.

Having thus described my invention, I claim as new and desire to secure by Letters Patent:

1. A finger shield comprising a jacket of crape paper, to closely fit the finger, having the entrance opening thereof cut off at an angle and provided with an internal flange, for the purpose described.

2. A finger shield comprising a jacket of corrugated sheet material, with the corrugations extending substantially longitudinally of the jacket and approximately throughout its length, whereby the corrugations adapt the diameter of the jacket to be expanded to fit fingers of different sizes.

3. A finger shield comprising a jacket having the edge of its inner or open end arranged at an inclination thereto such that when the shield is flattened one side thereof will extend beyond the other side, whereby the opening out of the shield is facilitated.

In testimony whereof I have signed my name to this specification, in the presence of two subscribing witnesses.

HOMER HARVEY FULTON.
